UNITED STATES PATENT OFFICE

PETER L. WILBUR, OF TUCKAHOE, NEW YORK, ASSIGNOR TO WIL-X-M'F'G CORPORATION, A CORPORATION OF NEW YORK

SPRAYING DEVICE

Application filed November 27, 1926, Serial No. 151,071. Renewed December 16, 1931.

This invention relates to spraying devices which may be used as a fire extinguisher or a sprayer for insecticides in which a stream of fluid is ejected from a container or reservoir by pressure, such as liquid pressure applied to the liquid in the container or by a reduction of pressure in the container by withdrawing and discharging the liquid from the container by a pumping mechanism.

10 It is a primary object of the invention to provide a device of this character wherein the pumping mechanism is adjustably mounted upon the exterior of and in communication with the interior of the container, which pumping mechanism in the operative position thereof is adapted to extend laterally of the container, and in the inoperative position thereof to be folded to lie in contiguous relation to the container forming a compact 20 structure readily stored and transported.

It is a further object of the invention to provide a spraying device of this character wherein the connection of the pumping mechanism with the container is through the 25 mounting thereon. The connection further permits the pump mechanism to be opened to the container in the operative position thereof, and to be shut off therefrom in the inoperative position of the pumping mechanism.

It is another object of the invention to provide a spraying device of this character wherein the pumping mechanism is arranged to inject and create an air pressure within the 35 container to exert an expelling force upon the liquid therein. The container is arranged with outlet means adapted to be placed in communication with the atmosphere when the pumping mechanism is in the operative position while at the same time the pumping mechanism is also placed in communication with the container. In the inoperative position of the pumping mechanism, the outlet means is adapted to be closed and the pumping mechanism shut off from the interior of the container.

Other objects and advantages will herein-after appear.

In the embodiment of the invention illustrated in the drawings there is provided a

pumping mechanism of the reciprocatory piston type to create an air pressure in the container or reservoir as the expelling force for the liquid, the container having a check valve controlled air inlet passage into and a liquid outlet passage from the container through a pump supporting and mounting member or bracket fixed upon the container, the pumping mechanism being fixed to a supporting member having a passage therethrough in communication with an air outlet port or ports from the pump cylinder, and the pump carrying discharge means in communication with the passage through the pump supporting member and by means of which supporting member the pump mechanism is pivotally mounted upon the pump supporting bracket upon the container. The passages in the pump supporting member as the pumping mechanism is moved to operative position are automatically placed in communication with the air inlet passage and liquid outlet passage in the supporting bracket, and as the pumping mechanism is adjusted or moved to inoperative position the air inlet and liquid outlet passages through the supporting bracket are automatically closed, means being provided to yieldingly and releasably retain the pumping mechanism in either its operative or inoperative position.

In the drawings accompanying and forming a part of this specification I have shown an embodiment of the invention in which Figure 1 is a side elevation of the upper part of the device showing the mounting of the pumping mechanism upon the container.

Figure 2 is a plan view looking at the top of Figure 1.

Figure 3 is a side elevation, the container being in section and the mounting mechanism in full with the pumping mechanism adjusted to its inoperative position.

Figure 4 is a perspective view of the bracket for mounting the pump upon the container with a part removed.

Figure 5 is a perspective view of the pump support whereby it is mounted upon the bracket shown in Figure 4.

Figure 6 is a sectional detail view taken on the line 6-6 of Figure 5 showing the air

passage in the pump support for connecting the pump with the container.

Figure 7 is a sectional detail view taken on the line 7—7 of Figure 5 showing the outlet passage in the pump support for connection of the discharge outlet means.

Figures 8 and 9 are sectional detail views to show the arrangement of the valve mechanism in the pump mounting bracket for controlling the discharge of the liquid from the container, and showing the valve mechanism in open and closed position respectively.

Figure 10 is a perspective view of a valve member of the discharge controlling mechanism shown in Figures 8 and 9.

Figure 11 is a sectional view showing means for releasably retaining the piston mechanism of the pump in its innermost position.

Figure 12 is a view looking at the end of the operating handle connected to the piston actuating rod and showing the arrangement of the means for releasably locking the piston in its innermost position.

Figure 13 is a cross sectional view of the pump showing a shield for pipes for connecting the pump outlet with the air inlet passage in the pump support and showing the pump in relation to means mounted on the container for releasably retaining the pump in inoperative position, and

Figure 14 is a sectional view of a piston and showing the connection thereof to its actuating rod.

The embodiment of the invention shown in the drawings comprises a reservoir or container 13 to contain the liquid to be discharged and in the use of the device as a fire extinguisher preferably consisting of carbon tetrachloride, said container being substantially of semi-circular form in cross section with the wall opposite the curved wall of the container bulged inwardly, as shown at 14 in Figure 2, to form a recess in the wall extending longitudinally thereof. The container is arranged with a filler opening in one end or the top having a removable closure cap, as at 15, and also has fixed at said end a member 16 for the connection of a looped strap for engagement over the shoulder of a person using the device to readily transport the same and permit of the use of both hands in manipulating the pump and directing the discharged stream.

A bracket 18 is fixed to one end of the container in interposed relation to the inwardly bulged portion 14 and the opposite wall of the container whereby to support and adjustably mount a pumping mechanism, in the present instance of the air pressure type. This bracket has a base portion whereby it is suitably mounted upon the container.

In the embodiment illustrated the pumping mechanism may embody either a single

or double acting pump, a pump of the single acting type being shown, air being discharged from the pump only during the forward stroke of the pump piston. The pump comprises a cylinder 35 having heads 36, 37 at opposite ends. The pump piston is in the form of a disk of flexible material 85 of greater diameter than the pump cylinder (Fig. 14), said disk being secured on a piston rod 48 between a pair of washers 86, 87 having threaded connection with the reduced end of the piston rod, the washer 86 being of substantially the same diameter as the pump cylinder and the washer 87 of slightly less diameter. The piston rod extends through the head 36 and has an operating handle 50 fixed thereto, the rod having a loose fit in the cylinder head 36 thus permitting the entrance of air into the pump cylinder in back of the piston which passes to the front of the piston between the piston disk 85 and cylinder, due to the flexibility of said disk, during the outward movement of the piston, and as the piston is moved into the cylinder the disk will spread making a substantially tight seal between the piston and cylinder forcing the air in front of the piston out through a port 88 (see Fig. 3) in the cylinder head 37. The port extends laterally and is connected by a pipe 89 with a passage 90 (see Fig. 6) in a pump support 54', the passage having an outlet port 91 with the outer end thereof of increased diameter and arranged in a boss 91' extending from the pump support as shown in said Figure 6 for a purpose to be herein-after described. This support has a recess 59' of circular shape in cross section wherein the pump is secured, and a bifurcated portion with perforations therein as shown at 92 in Figure 5 whereby it is pivotally mounted with the pump upon the mounting bracket 18 by engaging the bifurcated legs at the outer sides of a pair of ears or lugs 93, the ears having perforations to register with perforations in the bifurcated member 54'. Perforations are also provided in the plates 94 at the sides of the supporting brackets registering with the perforations in the lugs 93 and the bifurcated extensions 92. A headed stud 95 extends through the holes in the plates 94 and also through the previously mentioned registering perforations and is secured by a nut 96; thus providing a hinged joint whereby the pump may be swung relatively to the container.

The pump also carries a discharge nozzle 64' in an opening in the lateral extension of the cylinder head 37 which communicates with a pipe 63' connected to a passage 96 in the pump support 54' (Figures 5 and 7) having an outlet 97 with the outer end of the port of increased diameter and arranged in a boss 97' extending from the pump support. The wall of the passage 96 has an

opening therein in line with the port 97. A plug is fixed in the port 97 having a portion of reduced diameter or a pin extending axially through the port 97 to substantially 5 the end of the boss, as at 98, for a purpose to be hereinafter described. The bosses 91' and 97' when the pump is adjusted to operative position to extend laterally of the container are engaged in correspondingly 10 formed recesses 99, 99' in the mounting bracket 18 and sealed by engaging washers 102 of sealing material seated in said recesses, as clearly shown in Figures 8 and 9, placing the port 91 connected with the air 15 outlet of the pump in communication with an inlet port 100 to a passage 100' extending through the mounting bracket having an outlet in communication with a port in the container, as at 101. (Figure 3.)

20 The passage 100' is normally closed through the port 100 by a spring influenced valve comprising a circular head 103 engaging in a similarly formed enlargement at the inner end of the port 100 and having 25 a suitable material recessed in the end thereof to seat against the shoulder formed by the inner enlargement to seal the port, as clearly shown in Figure 8. The head is carried by or is integral with a stem 104 where- 30 by the valve is slidably mounted in a shouldered plug 105 threaded in an opening in the mounting bracket arranged coaxially of the port 100 and serving to connect said port with the passage 100', the valve being nor- 35 mally urged to its seat by a spring 106 coiled about the valve stem and confined be- 40 tween the valve head and the plug. This valve is unseated when the pump piston is discharged from the pump cylinder through 45 its connection with the port 100, the air thus being delivered from the pump into the container to create and store an expelling air pressure for the liquid therein.

50 Simultaneously with placing the pump in air communication with the container as above described, the nozzle 64' is likewise placed in communication with the container. This is effected when the boss 97' on the pump 55 support seats in the recess 99' in the mounting bracket. This places the port 97 in communication with a port 107 positioned axially with respect to the recess 99', and which in turn communicates with the passage 108 ex- 60 tending through the mounting bracket 18. A tube 34" opened at its lower end is connected to this passage, thus providing a duct through which liquid from the container 65 may be expelled. The container is formed with a dish-shaped bottom into which the expelling tube extends in order that practically all of the liquid in the container may be utilized. As the tube 34" is always immersed 70 in the liquid a seal is provided which pre-

vents the air from passing to the liquid outlet.

The interior of the container and thereby the liquid therein is shut off from the atmosphere through the port 107 by a spring influenced valve similar to the shut off valve for the air inlet 100. The valve comprises a head 103', of rectangular shape as shown in Figure 10 instead of circular as the valve head 103. The port 107 has an enlargement 75 of circular shape at the inner end for seating the valve and is of greater diameter than the cross sectional area of the valve head. The corners of the head are rounded, as shown at 109 in Figure 10, providing surfaces 80 engaging the wall of the port enlargement and leaving spaces between the sides of the valve head and port enlargement for the passage of the liquid to the port 107 when the valve is unseated. The valve also has a suitable 85 material seated in the end thereof to seat against the shoulder formed by the enlargement of the port 107 to seal the port when the valve is seated, as shown in Figure 9. The valve head is carried by a stem 104' slid- 90 ably mounted in a shouldered plug 106' threaded into an opening in the mounting bracket in co-axial alinement with the port 107, which opening serves to connect the pas- 95 sage 108 and port 107. The valve is normal- 100 ly urged to its seat by a spring 106' coiled about the valve stem and confined between the plug and valve head. It will be obvious that any pressure of the liquid in the container will exert a seating force upon the valve head 103', and to unseat the valve and open communication between the nozzle and the container through the port 107 the pin 98 extending through port 97 is adapted to 105 engage with a stem 110 extended from the valve head opposite to its carrying stem and through the port 107 when the pump is moved to operative position. As soon as the pump is moved to its inoperative position the pin 98 is moved out of engagement with the valve 110 pin and the valve is immediately seated by its spring.

To lock the pump in its operative position or that extending laterally of the container spring influenced detents 111 in the form of shouldered pins are carried in recesses in the opposite sides of the pump support, (Figure 5) and are normally projected to a predetermined extent beyond the sides of said support, said detents being adapted to automatically engage in perforations 112 in the side plates 94 of the mounting bracket 18 when the pump is positioned substantially horizontally to the axis of the container. The pump is readily released from this position by exerting a sudden force on the pump in the direction of the container.

The pump is releasably secured in its inoperative position in contiguous relation to and in the reduced portion 14 of the con- 130

tainer by a U-shaped resilient retaining member 113 (Figure 13) secured in the reduced portion of the container and adapted to embrace the pump cylinder at opposite sides beyond its greatest diameter. To facilitate the release of the pump from said retaining member the outer end of the head 37 has a recess 37' therein for the engagement of a finger or fingers whereby to readily grip and exert an outward pull on the pump.

To prevent the accumulation of foreign substances at the mounting of the pump support 54' the one edge of the side plates 94 is made of arcuate form, as at 94', having its center of curvature located at the center of the pump pivot support 95. A hood 114 is fixed to the pump support, said hood having a part to conform to the curvature of the plate edge 94' and its opposite ends arranged at slightly less than a right angle and bent to extend in parallel relation, as shown at 115, to embrace the outer surface of the end walls 94 the plates being pivotally supported upon the pump pivot support 95, as clearly shown in Figures 1 and 2. To prevent denting of the air conducting and nozzle carrying pipes 89, 63', or otherwise injuring the same, a shield of sheet metal 116 is provided, this shield extending between the cylinder head 37 and the pump support 54' and embracing the pump cylinder at the opposite sides thereof of greatest diameter.

To releasably lock the piston in its innermost position in the pump cylinder the cylinder head 36 (Figures 11 and 12) is extended beyond the end of the cylinder and arranged with an annular recess, as at 117. The pump operating handle has a recess 116' in the end and said recess has an annular enlargement 118. A member of resilient material 119, formed substantially of U shape is engaged in the annular enlargement 118, said member having the connecting portion arranged in an arc substantially the same as the curvature of the recess enlargement 118, and the legs arranged in parallel relation and spaced apart a distance substantially the same as the diameter of the annular recess in the extended portion of the cylinder end, said legs having their ends curved inwardly to extend into the enlargement of the recess 118 opposite to the connecting portion of said member, as clearly shown in Figure 24. By this arrangement as the piston is moved inward and the bottom of the recess in the end of the handle engages with the cylinder head 36 the legs of the resilient member will be sprung laterally to engage behind the shoulder formed by the annular recess 117 in the cylinder head. The operating handle may be readily released for operating the piston by exerting an outward pull on the handle thereby unseating the resilient retaining member from in back of the shoulder formed by the head recess 117.

While the spraying device is out of use or

in storage the pump 35 is secured contiguous to the body of the container and the container is sealed from the atmosphere by the valves 103, 103' arranged in the pump carrier 18. To place the device in operation the pump is positioned to extend laterally from the top of the container positioning the ports 91 and 97 of the pump support in communication with the ports 100 and 107 of the pump carrier, respectively, the air being forced from the pump through the ports 91 and 100 opening the valve 103 and permitting the air to enter the container through the passage 100'. The horizontal positioning of the pump opens the valve 103' in the port 107 allowing the liquid to be propelled from the container through the intake pipe 34'', passage 108, ports 107, 97, passage 63' and nozzle 64'.

It will be obvious that various modifications may be made in construction and arrangement of parts without departing from the scope of the invention.

Having thus described my invention I claim:

1. In a liquid spraying device, a liquid carrying container having a discharge outlet, a valve for the outlet normally positioned to close the outlet, a pumping mechanism to discharge the liquid from the container pivotally mounted upon the container on an axis extending transversely of the container to adjust the pump to position to extend in the plane of the longitudinal axis of and in contiguous relation to the container in the inoperative position thereof and to position to extend laterally of the container in the operative position thereof, a nozzle carried by the pump, and means operative when the pump is adjusted to operative position to positively actuate the valve to open the outlet and place the nozzle in communication with the outlet, said container having an air inlet arranged with a valve normally urged to closing position, and the pumping mechanism having an air outlet arranged with means to place said outlet in communication with the air inlet of the container when the pumping mechanism is moved to operative position.

2. In a liquid spraying device, a liquid carrying container, a pump having air inlet and outlet means, means to adjustably mount the pump upon the container comprising means fixed upon the container having a liquid outlet port from the container and an air inlet port to the container, and other means cooperating therewith having the pump fixed thereto with a pair of ports therethrough one an air port in communication with the air outlet means of the pump and the other a liquid outlet port having a nozzle connected thereto, said latter mounting means being movable with the pump and in one position thereof establishing communication through the corresponding ports in the mounting means fixed upon the container, and in another position of

the pump disestablishing communication through the ports in the mounting means fixed upon the container and closing said ports.

5 3. A liquid spraying device as claimed in claim 2, wherein the pump comprises a reciprocatory piston pump and the nozzle is arranged at one end of said pump and connected with the outlet port in the pump mounting

10 means by a tube, and the outlet port through the pump supporting means on the container has a tube in communication therewith in the container extending to the end thereof opposite to that upon which said member is fixed.

15 4. In a spraying device, a liquid carrying container having a pair of openings communicating with the interior thereof, an air pump having air inlet and outlet means, a nozzle carried by the pump, and means to ad-

20 justably mount the pump upon the container with the air outlet means thereof in communication with a port in said mounting means and the nozzle in communication with another port in said means, which ports are

25 adapted to be placed in communication with the interior of said container through said openings in a predetermined position of the pump, and in another position to move said ports out of communication with the interior

30 of the container.

5. In a spraying device, a liquid carrying container having a discharge outlet, an air pump having air inlet and outlet means, and means to adjustably mount the pump upon

35 the container constructed and arranged to open the air outlet means of the pump to the container and the discharge outlet to the atmosphere in a predetermined position of the pump and to shut off said pump outlet means

40 from the container and the discharge outlet from the atmosphere in another position of the pump.

6. In a spraying device, a liquid carrying container having a port communicating with the interior thereof, a valve for said port opening into and closing outward from the container, and a pumping mechanism for discharging the liquid from the container mounted

50 on the container to be adjusted to lie contiguous and in parallel relation to the longitudinal axis of the container in the inoperative position thereof and to extend transversely of the longitudinal axis and laterally of the container in the operative position, said pumping mechanism being arranged with means to place the same in communication with the container through the valved port when adjusted to operative position.

55 7. In a spraying device, a liquid carrying container having a port communicating with the interior thereof, a valve for said port opening into and closing outward from the container, discharge outlet means for the container including valve mechanism opening into and closing outward from the container,

and an air pump adjustably mounted on the container for creating an air pressure in the container adapted to be adjusted to lie contiguous to the container and out of communication with the container in the inoperative position thereof, and to extend laterally of the container in the operative position, said pump being adapted when moved to operative position to communicate with the interior of said container through said valved port, and to actuate the valve of the discharge outlet to establish communication therethrough to the atmosphere.

8. In a spraying device, a liquid carrying container, pump support means mounted thereon having passages therethrough adapted to establish communication with the interior of the container, one of said passages constituting an air inlet passage and the other a discharge passage for the liquid from the container, valves for said passages normally urged to closing position, and a reciprocatory piston air pump adjustably mounted on the pump support means and carrying a nozzle, said pump being adapted to be adjusted to lie contiguous to the container and out of communication with the container and to extend laterally of the container and arranged with means when adjusted to said position to connect the pump with the air inlet passage and the nozzle with the discharge passage.

9. In a spraying device, a liquid carrying container, pump support means mounted thereon having passages therethrough adapted to establish communication with the interior of the container, one of said passages constituting an air inlet passage and the other a discharge passage for the liquid from the container, valves for said passages normally urged to closing position to shut off the container from the atmosphere through said passages, an air pump having air outlet means, a nozzle carried at the end of said pump, a pump carrying element pivotally mounted on the pump support means and having passages therethrough in communication with the pump outlet and nozzle and whereby the pump is adapted to be adjusted to lie contiguous to the container and to be extended laterally of the container and when adjusted to said latter position placing the passages through the pump carrying element in communication with the air inlet and discharge passages in the pump support means and thereby connect the pump outlet means and the nozzle with the container.

10. The spraying device as claimed in claim 9, wherein the pump carrying element is arranged with means operative to move the valve for the discharge passage in the pump support means to open position as the pump is moved to operative position extending laterally of the container to open said passage and the container to the nozzle.

11. In a liquid spraying device, a liquid carrying container having a liquid discharge outlet, a valve for the outlet normally positioned to close the same, and pumping mechanism to discharge the liquid from the container pivotally mounted on an axis extending transversely of the container whereby said pump may be adjusted to extend in the plane of the longitudinal axis of and in contiguous relation to the container in the inoperative position thereof, and to extend laterally of the container in the operative position thereof, a nozzle carried by the pump, and means operative when the pump is adjusted to operative position positively to actuate the valve to open the outlet and place the nozzle in communication with the outlet.

12. In a spraying device, a liquid carrying container, a pump to discharge the liquid from the container, and means to mount the pump pivotally upon the container on an axis extending transversely thereof so as to have adjustment to extend longitudinally of and contiguous to the container in the inoperative position thereof or to a position to extend laterally of the container in the operative position thereof, comprising mounting means fixed to the container having a port therethrough in communication with the container, and a pump supporting member on said mounting means having a port therethrough in communication with the pump and adapted to be placed in communication with the port in said mounting means in the operative position of the pump, and out of communication with said port in the inoperative position of the pump.

13. In a spraying device, a container having discharge outlet means, a pump to discharge the contents from the container, and means to mount the pump pivotally upon the container so as to be capable of adjustment to extend longitudinally thereof and contiguous thereto in the inoperative position of the pump and laterally thereof in the operative position of the pump, said pump being arranged to shut off the discharge outlet means from the atmosphere and the container from the pump in said inoperative position and to open the discharge outlet means to the atmosphere, and to connect the container with the pump when the latter is in the operative position.

14. In a liquid spraying device, a liquid carrying container, bracket means fixed to said container having liquid outlet and air inlet ports therethrough in communication with the container, a pump having air outlet means, a nozzle carried by the pump, a pump support pivotally mounted on the bracket means to adjust the pump to lie longitudinally of and contiguous to the container or to extend laterally of the container, said support having ports therethrough in communication with the air outlet means of the

pump and the nozzle, said ports being adapted to be placed in communication with the ports in the bracket means, when the pump extends laterally of the container and out of communication with said ports when it extends longitudinally of the container.

15. In a liquid spraying device, a liquid carrying container having a discharge outlet and an air inlet, an air pump carrying a nozzle at one end, and means to mount the pump pivotally upon the container so as to have adjustment to extend longitudinally of the container or laterally thereof, said means being constructed and arranged to connect the nozzle with the discharge outlet from the container, and the pump with the inlet to the container in one position of the pump, and to shut off the nozzle from said discharge outlet and the pump from said air inlet in another position of the pump.

16. A liquid spraying device comprising a container, a discharge nozzle therefor, an air pump pivotally mounted upon the exterior of said container on an axis extending transversely thereof, whereby said pump may be adjusted to extend in the plane of the longitudinal axis of and in contiguous relation to the container in the inoperative position thereof, and to extend laterally of the container in the operative position thereof, an outlet from said pump adapted to communicate with the interior of said container, and means controlled by the position of the pump for establishing and disestablishing said communication.

17. A spraying device comprising a container for liquid, a discharge nozzle therefor, an air pump mounted on an axis extending transversely of the container whereby said pump may be adjusted to extend in the plane of the longitudinal axis of and in contiguous relation to the container in the inoperative position thereof, and to extend laterally of the container in the operative position thereof, an inlet to the container for the admission of air discharged from the pump, an outlet from the container for the discharge of liquid, and means for establishing an operative connection between the outlet from the container and the discharge nozzle when the pump is in one position, and for disestablishing said connection when the pump is in another position.

18. A liquid spraying device comprising a container, a discharge nozzle and an air pump pivoted coaxially upon the exterior of said container on an axis extending transversely thereof, whereby said nozzle and pump may be adjusted to extend in the plane of the longitudinal axis of and in contiguous relation to the container in the inoperative position thereof, and to extend laterally of the container in the operative position thereof, an air outlet for said pump, a pair of passageways communicating with the interior

of the container, and means for establishing an operative connection between one passageway and the nozzle and between the other passageway and the air outlet of the pump 5 when the nozzle and pump are swung to operative position.

19. A spraying device comprising a container for liquid, a discharge nozzle therefor, an air pump mounted on an axis extending 10 transversely of the container whereby said pump may be adjusted to extend in the plane of the longitudinal axis of and in contiguous relation to the container in one position thereof, and to extend laterally of the container in another position thereof, an air inlet to the 15 container, a liquid outlet from the container, means for establishing a connection between the air pump and the inlet to the container, and means for establishing a connection between 20 the outlet from the container and the nozzle, said connections being rendered inoperative when the pump is in said first position, and operative when the pump is in said second position.

25 20. A liquid spraying device comprising a container, a discharge nozzle and an air pump pivotally mounted as a unit upon the exterior of the container on an axis extending transversely of the container whereby the 30 nozzle and pump unit may be adjusted to extend in the plane of the longitudinal axis of and in contiguous relation to the container in the inoperative position thereof, and to extend laterally of the container in the operative position thereof, an air inlet to the 35 container, a liquid outlet from the container, means for establishing an operative connection between the air pump and the air inlet, and means for establishing an operative connection 40 between the liquid outlet and the nozzle, said last two means functioning conjointly when the pump and nozzle unit is swung to operative position.

45 21. In a liquid spraying device a liquid carrying container of semi-circular shape in cross section with the wall portion opposite the curved wall portion bulged inwardly to provide a recess extending longitudinally of the container, a liquid discharge outlet for the 50 container, a valve for the outlet normally positioned to close the same, and a reciprocating piston pump to discharge the liquid from the container pivotally mounted upon an end of the container, and adapted to be 55 adjusted to extend transversely of the container in the operative position, and to lie in the recessed portion of the container in the inoperative position, a nozzle carried by the pump, and means operative when the pump is 60 adjusted to operative position positively to actuate the valve to open the outlet and place the nozzle in communication with the outlet.

65 22. In a liquid spraying device, a liquid carrying container having a liquid discharge outlet, a valve for the outlet normally posi-

tioned to close the same, means for mounting a pump on the container to discharge liquid therefrom, said pump mounting means comprising means fixed to the container and other means pivotally mounted thereon on an axis 70 extending transversely of the container and to which latter means the pump is fixed, said mounting means rendering the pump adjustable to extend in the plane of the longitudinal axis of and in contiguous relation to the 75 container in the inoperative position thereof, and to extend laterally of the container in the operative position thereof, said pump being adapted to be placed in communication with the container through both said mounting means and to be opened to the container when the pump is adjusted to operative position, and to be placed out of communication with the container in the inoperative position, a nozzle carried by the pump, means operative 80 when the pump is adjusted to operative position positively to actuate the valve in the discharge outlet to open the outlet and place the nozzle in communication therewith, and a spring detent fixed upon one mounting member and cooperating with the other mounting member to retain the pump in its 85 adjusted position.

Signed at the city of New York, in the county of New York and State of New York 90 this 30th day of June, 1926.
